UNITED STATES PATENT OFFICE.

ELWIN S. ANDERSON, OF CANASTOTA, NEW YORK.

DESIGN FOR A SLICER AND GRATER.

SPECIFICATION forming part of Design No. 34,655, dated June 11, 1901.

Application filed April 22, 1901. Serial No. 57,027. Term of patent 14 years.

To all whom it may concern:

Be it known that I, ELWIN S. ANDERSON, a citizen of the United States, residing at Canastota, in the county of Madison and State 5 of New York, have invented and produced a certain new and original Design for a Slicer and Grater; and I do declare the following to be a full, clear, and exact description of the invention, such as will enable others skilled 10 in the art to which it appertains to make and use the same.

The invention relates to a new and original design for a slicer and grater designed for slicing, shredding, scalloping, and grating 15 vegetables; and it consists of a design of the configuration shown in the accompanying drawings, in which—

Figure 1 is a perspective view, and Fig. 2 is a longitudinal sectional view.

20 The leading feature of the design comprises a rectangular body portion 1, provided with

a wire handle A, a diagonal slit 2, the edges B and C of which are bent in opposite directions and reduced to a cutting edge, also edges 3 and 4, bent over the wire A, horizontal parallel rows of inclined cutting-lips 5, arranged at the base of openings 6, a diagonal slit 7, one wall of which is bent rearwardly and the other wall of which is bent forwardly and fluted, and horizontal rows of grating- 25 30 apertures 8, the walls of which are concaved upward, forming a circular scraping edge.

What I claim is—

The design for a slicer and grater, as herein 35 shown and described.

In testimony whereof I have hereunto set my hand in presence of two subscribing witnesses.

ELWIN S. ANDERSON.
